US0D1031547S

(12) **United States Design Patent** (10) **Patent No.:** **US D1,031,547 S**
(45) **Date of Patent:** **** Jun. 18, 2024**

(54) **HOOD FOR VEHICLE**

(71) Applicant: **HUMAN HORIZONS (JIANGSU) TECHNOLOGY CO., LTD.**, Jiangsu Province (CN)

(72) Inventor: **Zhenwu Zhang**, Jiangsu Province (CN)

(73) Assignee: **HUMAN HORIZONS (JIANGSU) TECHNOLOGY CO., LTD.**, Jiangsu Province (CN)

(**) Term: **15 Years**

(21) Appl. No.: **29/846,807**

(22) Filed: **Jul. 19, 2022**

(30) **Foreign Application Priority Data**

Mar. 14, 2022 (CN) 202230131098.X

(51) **LOC (14) Cl.** **12-08**

(52) **U.S. Cl.**

USPC **D12/173**

(57) **CLAIM**

The ornamental design for a hood for vehicle, as shown and described.

DESCRIPTION

FIG. 1 is a top view of a hood for vehicle showing my new design;

FIG. 2 is a bottom view thereof;

FIG. 3 is a back view thereof;

FIG. 4 is a front view thereof;

FIG. 5 is a left side view thereof;

FIG. 6 is a right side view thereof;

FIG. 7 is a perspective view thereof;

FIG. 8 is a rear, top perspective view thereof; and,

FIG. 9 is an enlarged view of a side vent region of the hood for vehicle indicated by “9” in FIG. 8, wherein the opposite side vent region on the hood for vehicle is a mirror image thereof.

1 Claim, 9 Drawing Sheets
